UNITED STATES PATENT OFFICE.

JOSEPH E. BOND, OF APPLETON, WISCONSIN.

AGITATOR.

Application filed March 5, 1928. Serial No. 259,081.

My invention relates to the art of paper making and particularly to means for agitating paper pulp.

In the development of the art it has been found possible to greatly increase the capacity of a given equipment by increasing the density (or, in other words, lessening the fluidity) of the pulp during its treatment preceding delivery to the Fourdriniers. While in the old practice a 2½% pulp was considered proper and of the maximum density possible, it is now common to deal with 6% solutions, with correspondingly increased production capacity. However, many difficult problems are encountered in handling pulp of this density due to its lack of fluidity and its tendency to mass or cake in the storage or treatment tanks and containers. This tendency is inherent in the nature of the material under treatment due to its fibrous character and to the physical law of attraction of solids. The liquid within which the solids are carried serves merely as a supporting medium therefor and facilitates rather than hinders the massing and intertwining of the fibers.

To avoid massing and stratifying of the pulp in the liquid and to maintain a uniform density throughout the entire body of material it must be kept in motion and the motion producing means should have a tendency to break up and tear apart any large or small masses of pulp. In the old practice the mixture was kept in motion by means of paddles or impellers in the tank, but this apparatus had very little tendency to break up masses of pulp, and was wholly ineffective with stock of increased density. Furthermore, such apparatus required an outlay of power not commensurate with the results secured.

The tanks, chests or containers which are in place and must be utilized for the new plan of operation are of many and varied forms, all of great size, some narrow and of great length, some deep and some round. The problem has been, therefore, to provide means applicable to these various forms of tanks that would insure effective circulation, the breaking up of pulp masses and the maintenance at all times of a proper consistency throughout the whole volume of material, with a minimum of power expenditure.

The invention will be more readily understood by reference to the accompanying drawings, of which—

Fig. 1 is a plan view of an agitator layout constructed in accordance with my invention;

Fig. 2 is an end elevation thereof, and

Fig. 3 is a sectional view on the line 3—3 of Fig. 1.

In the drawings, I have illustrated a rectangular tank having side walls 10, 11 and end walls 12, 13. The tank is divided into compartments by three longitudinally extending walls 14, 15, 16 which extend from end to end of the tank thereby forming compartments A, B, C, D. Compartments A and B are in communication through the conduit or passageway 17, while compartments C and D are in communication through the passageway 18. Compartments B and C may likewise be placed in communication by means of passages 19 if so desired.

Two pumps 20, 21 are located outside of the end wall 13, the pumps being of the propeller type operated by suitable motors. An inlet pipe 22 from the pump 20 enters compartment B near the floor thereof, and a pipe 23 enters compartment C in a similar manner. A discharge pipe 24 from the pump 20 connects with tank D at a level above that of the inlet, while the pipe 25 connects the motor 21 to the tank A.

With the motors in operation and the tanks containing a quantity of stock, material is drawn into the pumps from the tanks B, C and is discharged into the tanks A, D. However, the material discharged into tank D passes through the conduit 18 into tank C from which it is withdrawn into the pump 95 other than that which discharged it and is thereafter delivered into tank A. Thus the entire body of material within the four compartments is circulated throughout the entire area of the tank. The agitation by the 100 pump and the constant circulation of the material insures proper consistency at all times.

I claim:

1. In combination a tank, walls dividing 105 said tank into a plurality of side by side compartments, two pumps each having an inlet from separate compartments and an outlet into other separate compartments, and means connecting the compartment that re- 110

ceives the material discharged from one pump with the compartment that delivers material to the other pump.

2. An agitator comprising in combination 5 a tank having a plurality of walls dividing the tank into adjacent compartments, a plurality of pumps each having an inlet and discharge connection to separate compartments, the discharge from one pump being 10 into a compartment that is in communication with a compartment that delivers material to another pump.

3. In combination, a plurality of adjacent tanks laterally adjacent tanks being in communication with each other, a pump having 15 an inlet from one compartment and an outlet into another compartment, another pump having an inlet and outlet connecting with other compartments, the discharge from one 20 pump being into a tank that delivers material to the other pump.

4. In combination, a tank, walls dividing said tank into four compartments, a pump having an inlet connected to one compartment

ment and a discharge connection into another 25 compartment, a second pump having inlet and discharge connections with other compartments and means connecting said compartments whereby the material discharged from one pump is caused to return to another 30 pump.

5. In apparatus of the class described, the combination of a substantially square liquid tank, said tank being longitudinally divided into four independent tanks, the two end 35 tanks each having a communicating opening near the bottom thereof to an adjacent middle tank, and two pumps, said pumps each having an inlet connection with the bottom of each of said middle tanks, and each 40 pump having a discharge connection near the top of said end tanks, the respective inlet and outlet connections being located in alternate tanks.

In testimony whereof I have affixed my 45 signature.

JOSEPH E. BOND.
